UNITED STATES PATENT OFFICE.

JOSEF BÁRCZ, (NOW BY JUDICIAL CHANGE OF NAME JOSEPH BÁRCZ,) OF COLOGNE-EHRENFELD, GERMANY.

FLYING-MACHINE.

1,073,855.

Specification of Letters Patent. Patented Sept. 28, 1913.

Application filed December 16, 1911. Serial No. 666,182.

To all whom it may concern:

Be it known that I, Josef BÁRCZ, a subject of the German Emperor, and resident of 82 Leostrasse, Cologne-Ehrenfeld, Germany, have invented certain new and useful Improvements in Flying-Machines, of which the following is a specification.

My invention relates to flying machines and it consists firstly in the provision of adjustable gliding wings fitted with flapping wings which latter have short turn-over wings as well as flaps which are closed on three sides and open at the rear side.

A further feature of the invention resides in the shifting and sliding arrangement of the rudder so that the latter can serve both for vertical and lateral steering, and in the constructive formation of the same.

Lastly, the invention consists also in the provision of tubular frame-work which serves as liquid fuel container.

The invention is shown in the accompanying drawings by way of an example, and in these drawings:—

25 Figure 1, is a longitudinal section. Fig. 2, is a plan. Fig. 3, is a cross-section of the flying machine. Figs. 4-6, show details of construction hereinafter referred to.

To the frame 1 are hinged the gliding wings 2 which can be adjusted or set at any angle by means of stretching-cords 3, see dotted lines in Fig. 3. This will allow, during transport on the ground, of the said wings being placed parallel with the frame.

35 The ascending and forward movement of the flying machine is obtained by means of flapping wings 4 which are operated from the motor 5. The wings 4 are provided with flaps 6 (see Figs. 2 and 4) which at the upper stroke of the wings allow the air to pass through them while at the downstroke they lie against the frame. The flaps 6 are attached to the frame of the flapping wings by hinges and their deflection is limited by bolts 7. Springs 8 serve for instantly closing the flaps 6 in their highest position at the return motion. The flaps are closed on three sides but open at the rear side.

For increasing the effect of the flapping wings 4, the front of same is fitted with a short removable wing 9 which, at the move-

ment of the wings 4, are turned by rods 10 into the position shown by dotted lines in Fig. 4. This is obtained by having on the shaft, which is firmly connected with the articulated part 9 of the wings 4, a two-armed lever 11 from which crossed rods 10 pass to the bearing bracket 12 fixed to the gliding wings 2. The operation of this mechanism is as follows:—At the motion of the flapping wings 4, the bracket 12 which is fast with the gliding wings 2, remains in its position, but by reason of the position of the turning points of the rods 10, the short wing 9 will be caused to take the position shown by dotted lines in Figs. 1 and 4. Therefore, with the downstroke of the wing 4 a reduced surface is obtained.

In the interior of the flying frame are placed steering organs whereby the rudder 20 is rendered slideable so as to increase the carrying capacity, while at the same time the transport over ground is facilitated by reason of the drawing-in of the rudder. For this purpose, the steering shaft proper 75 13 is mounted in a hollow shaft 14 and adjustably held therein by set screws 15. The hollow shaft 14 is fitted at its forward end with a toothed wheel 16 which meshes with a toothed sector 17 fast on a shaft 18 mounted near one side of the flying frame and fitted at its forward end with a steering lever 19.

As lateral steering is to be effected by reducing the carrying capacity of the rudder, 85 it is here arranged to turn the steering lever sidewise so that the sector and the wheel 16 turns the hollow shaft 14 with the steering shaft 13 and the rudder 20. This reducing of the carrying capacity of the rudder will 90 naturally cause the frame or rather the rudder to be lowered. Simultaneously with the lowering of the rudder, there occurs a lateral displacement of the flying machine so that the axis thereof is deflected from its 95 previous course. The lowering of the rudder toward the one or the other side is shown in the Figs. 5 and 6.

In order to use the rudder for vertical steering it is adjusted by means of a lever 100 21 which is connected with telescoping rods 22 controlling a two-armed lever 23 which

transmits its movements by rods 24 to the rudder 20. The rods as also the steering shaft are suitably adjusted endwise and then secured by set screws or otherwise so as to avoid unintentional telescoping of same.

At the lower flying frame there are four chain pulleys 28 which carry the seat 27 for the pilot and passengers, the arrangement being such as to insure balancing with varying loads. The car can also be connected with the lever 21 so that the rudder 20 shall be automatically regulated under great tossing of the flying machine. The car may advantageously be suspended from the middle cross bar 29 of the flying frame. It is to be remarked that the car must be rigidly fixed to the frame during the transport over ground. This can be effected by means of a nut on the pivot bolt 30 whereby the car can be held rigidly in position. This is necessary because the car is fitted with the third runner wheel 31 which latter may be used for steering by means of the hand-wheel 32.

The wings 4 receive movement from the motor through the intervention of rods 33 of eccentrics, and which rods are attached to a block 34 moving in a slotted guide 35 and operating connecting rods 36 with cranks 37. The crank-shaft 38 is mounted in bearings 39 fixed to the flying frame 1. The crank-shaft is connected with the shaft 40 of the flapping wings 4 by means of universal joints 41 so that said wings can be operated in any position of the gliding wings or planes 2. The flying frame is composed of tubes which serve as reservoirs for liquid fuel for the motor.

It may be remarked that the driving mechanism, when the flight is in the direction of the wind, can be temporarily uncoupled and that only at more or less long intervals a few strokes of the flapping wings may be carried out. For this purpose the driving mechanism is fitted with any suitable friction clutch one part of which is fast on the motor shaft.

Before using the flying machine it will naturally be necessary to properly adjust and fix the telescoping and collapsible parts of the machine.

What I claim as my invention and desire to secure by Letters Patent is:—

1. A flying machine, comprising a frame, adjustably disposed gliding wings, flapping wings, attached to the latter movable flaps in the frame of said flapping wings and automatically turn-over surfaces at the outer side of the frame of said flapping wings said flaps of the flapping wings being closed at three sides, substantially as set forth.

2. A flying machine, comprising a frame, adjustably disposed gliding wings, flapping wings attached to the latter movable flaps in the frame of said flapping wings and automatically turn-over surfaces at the outer

side of the frame of said flapping wings said articulated surfaces being turned over by means of a two-armed lever fast on the axis of said surfaces and having the ends pivotally connected with crossed rods the other ends of which rods are held in stationary positions, substantially as set forth. 70

3. A flying machine, comprising a frame, adjustably disposed gliding wings, flapping wings, attached to the latter, the shaft of 75 said flapping wings being journaled on said gliding wings and arranged at an acute angle with the longitudinal axis of said flying frame, movable flaps in the frame of said flapping wings and automatically turn-over surfaces at the outer side of the frame of said flapping wings, said flaps of the flapping wings being closed at three sides, substantially as set forth.

4. A flying machine, comprising a frame, 85 adjustably disposed gliding wings, flapping wings, attached to the latter, the shaft of said flapping wings being journaled on said gliding wings and arranged at an acute angle with the longitudinal axis of said flying frame, movable flaps in the frame of 90 said flapping wings and automatically turn-over surfaces at the outer side of the frame of said flapping wings, said flaps of the flapping wings being closed at three sides, a 95 motor arranged in said frame, a crank operated by said motor, and a universal joint for connecting said crank to said shaft of said flapping wings, substantially as set forth.

5. A flying machine, comprising a frame, 100 adjustably disposed gliding wings, flapping wings, attached to the latter, the shaft of said flapping wings being journaled on said gliding wings and arranged at an acute 105 angle with the longitudinal axis of said flying frame, movable flaps in the frame of said flapping wings and automatically turn-over surfaces at the outer side of the frame of said flapping wings, said flaps of the 110 flapping wings being closed at three sides and a steering shaft turnable in said frame, a rudder connected with said steering shaft and turnable on its transverse middle axis, and a lever connection for turning said rudder on its transverse middle axis, substantially as set forth.

6. A flying machine, comprising a frame, 115 adjustably disposed gliding wings, flapping wings, attached to the latter, the shaft of 120 said flapping wings being journaled on said gliding wings and arranged at an acute angle with the longitudinal axis of said flying frame, movable flaps in the frame of said flapping wings and automatically turn-over surfaces at the outer side of the frame of said flapping wings, said flaps of the flapping wings being closed at three sides, a 125 steering shaft turnable in said frame, a rudder connected with said steering shaft and 130

turnable on its transverse middle axis, and rods for turning said rudder on its transverse middle axis, said steering shaft and said rods being composed of several telescoping parts, substantially as set forth.

In testimony whereof I have hereunto signed my name this 1st day of December

1911, in the presence of two subscribing witnesses.

JOSEF BÁRCZ.
